CLAIM

The ornamental design for an ice maker door and kick plate as shown and described.

DESCRIPTION

FIG. 1 is a front, right perspective view of an ice maker door and kick plate showing our new design in an illustrative environment mounted to an exterior surface of an ice maker; FIG. 2 is a front, right perspective view of the ice maker door and kick plate of FIG. 1;

FIG. 3 is a front elevation view of the ice maker door and kick plate of FIG. 2;

FIG. 4 is a top plan view of the ice maker door and kick plate of FIG. 2;

FIG. 5 is a bottom elevation view of the ice maker door and kick plate of FIG. 2;

FIG. 6 is a left elevation view of the ice maker door and kick plate of FIG. 2;

FIG. 7 is a right elevation view of the ice maker door and kick plate of FIG. 2; and,

FIG. 8 is a front, left perspective view of the ice maker door and kick plate of FIG. 2 with a handle mounted on a right side of the door.

The broken lines in FIG. 1 are included for the purpose of illustrating the ice maker door and kick plate in its environment and form no part of the claimed design. The back of the ice maker door and kick plate are unornamented and form no part of the claimed design.
